United States Patent Office

Des. 220,299
Patented Mar. 23, 1971

220,299

STOVE

Norman Schott, Burnaby, British Columbia, Canada, assignor to Dickinson's Limited, Burnaby, British Columbia, Canada

Filed Nov. 21, 1969, Ser. No. 20,222

Term of patent 7 years

Int. Cl. D7—04

U.S. Cl. D81—10

FIG. 1 is a front elevation of the stove;
FIG. 2 is a frontal, side, and top perspective view of the stove;

FIG. 3 is a side elevation of the stove;

FIG. 4 is a rear elevation of the stove on a reduced scale.

The opposite side of FIG. 3 is a mirror image thereof.

I claim:

The ornamental design for a stove, as shown and described.
